US00D552637S

(12) **United States Design Patent** (10) **Patent No.:** **US D552,637 S**
Dore (45) **Date of Patent:** **** Oct. 9, 2007**

(54) **ABRASIVE BLASTING APPARATUS**

(75) Inventor: **David James Dore**, Derbyshire (GB)

(73) Assignee: **Quill International Industries PLC**,
Melbourne, Derbyshire (GB)

(**) Term: **14 Years**

(21) Appl. No.: **29/250,209**

(22) Filed: **Nov. 6, 2006**

(51) **LOC (8) Cl.** **15-09**

(52) **U.S. Cl.** **D15/122**

(58) **Field of Classification Search** **D15/122,**
D15/124; 451/75, 88-90, 99, 100, 101, 410,
451/426, 438

(57) **CLAIM**

The ornamental design for an abrasive blasting apparatus, as shown and described.

DESCRIPTION

FIG. 1 is a perspective view of the abrasive blasting apparatus showing my design.

FIG. 2 is a front view thereof;

FIG. 3 is a back view thereof;

FIG. 4 is a side elevation view thereof;

FIG. 5 is an opposite side elevation view thereof; and,

FIG. 6 is a top plan view thereof.
